UNITED STATES PATENT OFFICE.

GEORGE ATOCK, OF CARACAS, VENEZUELA.

LIQUID-FUEL BURNER FOR FURNACES OF LOCOMOTIVE-BOILERS AND FOR OTHER FURNACES.

1,332,480.

Specification of Letters Patent.

Patented Mar. 2, 1920.

Application filed July 28, 1919. Serial No. 313,750.

To all whom it may concern:

Be it known that I, GEORGE ATOCK, a subject of the King of Great Britain and Ireland, residing at Venezuela, South America, (whose post-office address is La Guaira and Caracas Railway, Caracas, Venezuela, South America,) have invented certain new and useful Improvements in Liquid-Fuel Burners for the Furnaces of Locomotive-Boilers and for other Furnaces; and I do hereby declare the following to be a full, clear, and exact description of the invention, such as will enable others skilled in the art to which it appertains to make and use the same.

This invention relates to improvements in liquid fuel burners for the furnaces of locomotive boilers and for other furnaces. Such burners as heretofore employed have usually consisted of a body portion comprising a chamber in which are fitted a steam jet nozzle or injector and an air nozzle, the arrangements being such that the oil and atmospheric air which enter the burner body or chamber, through suitable inlet passages, are by the action of the steam jet drawn and forced forward in the burner body and out through suitable outlet orifices in the front end of the burner body into the furnace, a separate steam passage leading into a chamber in the lower portion of the burner body so as to deliver separate small jets of steam through small orifices situated below the aforesaid outlet orifices at the front end of the burner.

The present invention consists in an improved burner which while being simple in construction insures thorough mixing of the steam, oil and air within the burner body and effective delivery of the mixture into the furnace chamber.

According to this invention the liquid fuel burner comprises an upper chamber in the burner body for the oil or liquid fuel and extending substantially throughout the length and breadth of said body, a mixing chamber in said burner body extending beneath the greater portion of the oil chamber and separated therefrom by a partition or wall, a steam jet chamber in rear of and communicating with the mixing chamber, a steam jet nozzle in said jet chamber, air passages leading from the atmosphere into said jet chamber in rear of the forward end of the nozzle, a multiplicity of holes in the front wall of the mixing chamber, and a

multiplicity of holes in said partition and arranged so that the oil falls in drops, like rain, into substantially all parts of the mixing chamber wherein the falling drops are met by and mixed with the blast of steam 60 and air by which the oil is driven forwardly through the holes in the front wall of the mixing chamber, into the furnace. A steam inlet is arranged in rear of the steam jet nozzle and there is provided a steam passage 65 extending longitudinally of the burner body and below the mixing chamber from the steam inlet to a transverse passage or channel adjacent the front end of the burner body, and a plurality of small passages leading from said transverse passage out of the burner body below the outlets for the combustible mixture from said mixing chamber, the steam issuing from said small passages tending to drive the combustible mixture, together with any oil that may run down the end face of the burner into the furnace.

The invention further consists in a liquid fuel burner constructed and adapted to operate substantially as hereinafter described with reference to or as shown in the accompanying drawings, in which:

Figure 1 is a longitudinal sectional elevation of a burner according to this invention.

Fig. 2 is a plan of the burner with the top plate or cover removed.

Fig. 3 is a rear end view of the burner, and

Fig. 4 a front end view of the burner.

Like reference numbers indicate corresponding parts of the several figures of the drawings.

1 is the body of the burner, 2 and 3 are respectively the upper and lower chambers in the burner body, these chambers being separated from each other by a partition or wall 5 which as shown is an integral part of the burner body, the upper chamber 2 is the chamber which receives the oil or liquid fuel 95 from the source of supply and the lower chamber 3 is the mixing chamber from which the combustible mixture is driven out through the outlet apertures 6 in the front end of the burner. 4 are the hereinbefore 100 mentioned holes in the partition or wall 5 these holes forming communication between the chamber 2 and the chamber 3, a suitable number of these holes 4 being provided, and as shown, the holes are preferably counter- 105 110

sunk. 7 is the steam jet nozzle or injector fitted in the burner body in a chamber 8 therein, the rear end of this nozzle 7 in the example shown having a flange 7^a which abuts against a suitable annular recess or shoulder in the burner body. 9 is a screwed aperture in the rear end of the burner body adapted to receive the outlet end of the usual pipe through which steam is supplied to the injector nozzle 7. 10 are passages through the sides of the burner body, the said passages being open at their outer ends to atmosphere and open at their inner ends at a suitable position in the chamber 8, preferably as shown well to the rear of the forward or outlet end of the nozzle 7. 11 is a steam passage in the burner body below the mixing chamber 3, the rear or inlet end of this passage communicating with the aperture 9 through which steam is admitted to the burner body, and 12 is the hereinbefore mentioned transverse channel in the burner body with which the forward or outlet end of the passage 11 communicates; 13 are three small passages leading from the channel 12 through the front end of the burner body below the outlet holes 6. In the example shown the top of the burner body and of the chamber 2 therein consists of a separate plate or casting 14 provided with a screw socket 15 adapted to receive the usual pipe through which the oil or liquid fuel passes from the supply into the oil chamber 2; 16 are screws fastening the cover 14 to the burner body. If desired however the top of the burner body might consist of an integral part of the casting. 17 Fig. 2 are screwed holes in the partition or wall 5 into which the screws 16 are screwed for securing the cover 14 on the burner body. 18 Fig. 2, are holes in lateral projections or lugs formed on the rear end of the burner body, these holes being provided for the purpose of securing the burner in position for use for instance by means of bolts passing through the holes 18. In working, the oil admitted to the chamber 2, through the inlet 15, flows through the holes 4 in the wall 5 and falls into the chamber 3 in drops, and these drops are met by the combined jets of steam and air admitted to the chamber 3 through the steam nozzle or injector 7 and the air passages 10, the air being drawn in through the passages 10 by the action of the steam jet 7, by which the mixture of oil, air and liquid is forced forward and out through the outlet holes 6 as hereinbefore mentioned. At the same time that steam is admitted to the nozzle 7 steam is also admitted to the steam passage 11, channel 12 and passages 13, the steam issuing from the passages 13 at the front end of the burner, tending to drive the combustible mixture, issuing from the outlets 6, into the furnace.

Variations in the details of construction and arrangement of the parts of the burner as above described with reference to the drawings might be made without departing from the main features of the invention.

What I claim as my invention and desire to secure by Letters Patent is:—

1. A liquid fuel burner, comprising a casing provided with a substantially horizontal plate dividing it into an oil chamber and a mixing chamber, said plate having perforations through which the oil passes in drops from the oil chamber to the mixing chamber, said mixing chamber having a substantially vertical wall at one end of the casing provided with a series of outlet holes, said casing having also at its other end a steam jet chamber and lateral passages for admitting air thereto, and a nozzle secured in the said steam jet chamber between the lateral air passages and operating to project a jet of steam and air against the drops of oil as they fall from the said perforated plate into the mixing chamber.

2. A liquid fuel burner, for the furnaces of locomotive boilers and for other furnaces, comprising an upper chamber in the burner body for the oil or liquid fuel and extending substantially throughout the length and breadth of said body, a mixing chamber in said burner body extending beneath the greater portion of the oil chamber and separated therefrom by a partition or wall, a steam jet chamber in rear of and communicating with the mixing chamber, a steam jet nozzle in said jet chamber, a steam inlet in rear of the steam jet nozzle, air passages leading from the atmosphere into said jet chamber in rear of the forward end of the nozzle, a multiplicity of holes in the front wall of the mixing chamber, a multiplicity of holes in said partition and arranged so that the oil falls in drops, like rain, into substantially all parts of the mixing chamber wherein the falling drops are met by and mixed with the blast of steam and air by which it is driven forwardly, through the holes in the front wall of the mixing chamber, into the furnace, a steam passage extending longitudinally of the burner body and below the mixing chamber from the steam inlet to a transverse passage or channel adjacent the front end of the burner body, and a plurality of small passages leading from said transverse passage out of the burner body below the outlets for the combustible mixture from said mixing chamber.

In testimony whereof I affix my signature, in presence of two witnesses.

GEORGE ATOCK.

Witnesses:

EARL PRYOR,
EMMANUEL JOHNSON.
